UNITED STATES PATENT OFFICE.

CLINTON H. HULBERT, OF CHICAGO, ILLINOIS.

DEVICE FOR PRODUCING OR REPRODUCING SOUND.

Application filed March 21, 1917, Serial No. 156,428. Renewed October 18, 1922. Serial No. 595,463.

To all whom it may concern:

Be it known that I, CLINTON HORACE HULBERT, a citizen of the United States, residing at Chicago, county of Cook, and State of Illinois, have invented certain new and useful Improvements in Devices for Producing or Reproducing Sound, of which the following is a specification.

This invention relates to devices for producing or reproducing sound, and particularly to telephone receivers. With the usual construction of receivers now generally employed, not more than two magnetic pole pieces are used, and as a result, the thin diaphragm becomes easily saturated opposite the pole pieces, so that only a limited quantity of magnetic lines of force may pass through, thereby limiting the amount of current which may be effectively utilized.

I have provided means whereby the effective magnetic area of the diaphragm may be increased with the result that an increased quantity of magnetic lines of force may pass from the pole pieces through the diaphragm causing greater resonance and thereby increasing the tonal quality of the instrument. The device may be used as a receiver or a transmitter, but it is particularly applicable as employed in annunciating horns, such as employed in railway stations, public halls and the like.

In carrying out my invention, I preferably arrange the electro-magnets in multiples of two, in inwardly projecting circular groups about a common center, the opposite poles being disposed in alternating relation, whereby the magnetic attraction exerted upon the diaphragm is equally disposed about the axis of said diaphragm. I also prefer to arrange the permanent magnets, to which the electro-magnets are attached, of such form that their outer ends are of greater cross sectional area than the inner ends, so that there will be heavy lines of magnetic force to concentrate at the pole points. Theoretically, the greater the number of pole pieces, the greater the resonance of the diaphragm, but for practical purposes, I have found that from six to eight pole pieces efficiently distribute the electro-magnetic lines of force throughout the diaphragm.

For the purpose of illustration, I have shown two practical forms of my invention, it being understood, of course, that changes

in form, proportion, and minor details of construction may be resorted to, without departing from the spirit of the invention, or sacrificing any of its advantages. 60

In the drawings:—

Figure 1 is a vertical longitudinal sectional view through a telephone receiver constructed in accordance with my invention; 65

Figure 2 is a transverse sectional view through the same, and

Figure 3 is a vertical longitudinal sectional view through an annunciating receiver. 70

Referring now to the drawings by numerals of reference, 1 designates a casing having a removable cover 2 with a central opening 3 of usual construction, the diaphragm 4 being interposed between the edge of the casing 1 and the cover 2 in the usual manner. Within the casing 1 are a plurality of permanent magnets 5 radially disposed about a common center and clamped to the bottom of the casing 1 by a plate 6 and fastening devices 7. The outer ends of the permanent magnets 5 are preferably of greater cross sectional area than their inner ends, and said outer ends are provided with offset portions to which the poles of the electro-magnetic windings 10 are secured, preferably by fastening devices 11. It will be observed that the poles 9 of the magnetic windings 10 project inwardly and upwardly toward a common center, the ends of said magnets being relatively close to the comparatively thin diaphragm 4. Inasmuch as the pole pieces 9 are arranged in multiples of two (in the present instance there being four pairs) the lines of magnetic force will be fractionally distributed about the common center over area in excess of that usually employed for devices of this character so that stronger current may be employed and greater resonance obtained from the diaphragm, resulting in a relatively loud tone. 95

If desired, the tonal quality of the device may be varied through the medium of the contact bar 12 on the rotating shaft 13, whereby the bar 12 may be cut in or cut out certain electro-magnets. 105

In Figure 3, I have shown a slightly modified form of device embodying the same generic principle, the latter device being especially adapted for annunciators, such as employed in railway stations and the like. 110

In this form the casing 14 is provided with relatively strong permanent magnets 15 having pole pieces 9^a with the magnetic windings 10^a arranged in substantially the same relation as those described with respect to Figures 1 and 2, the opening 3^a leading into a horn 16.

From the foregoing, it will be seen that I have provided a device of the class described in which a relatively thin diaphragm may be adapted to receive magnetic lines of force of comparatively great intensity because multiple paths are provided for the lines of force so the aggregate current is fractionally distributed through the diaphragm.

It is to be understood, of course, that in order to add rigidity to the structure heretofore described, the casings may be

nearly filled with an embedding material 20 such as wax or the like, as is somewhat now in practice in devices of similar character.

I claim:

In a device of the class described, permanent magnets, electro-magnets connected thereto consisting of six or more located all on one side of the diaphragm arranged in pairs of like poles, the poles of said electro-magnets being disposed in circular series, the north and south poles being arranged in alternating relation and a diaphragm cooperating with said poles.

The foregoing specification signed at Washington, District of Columbia, this 20th 35 day of March, 1917.

CLINTON H. HULBERT.
